UNITED STATES PATENT OFFICE.

QUINCY G. SHELDON, OF ELBURN, ILLINOIS.

POST-MOLD.

1,111,808.

Specification of Letters Patent. Patented Sept. 29, 1914.

Application filed October 4, 1913. Serial No. 793,393.

To all whom it may concern:

Be it known that I, QUINCY G. SHELDON, a citizen of the United States, residing at Elburn, in the county of Kane and State of Illinois, have invented certain new and useful Improvements in Post-Molds, of which the following is a specification.

The mold which is the subject of the present invention is designed for making concrete or artificial stone fence posts, and its object is to provide a simple and inexpensive mold by which the posts may be rapidly and cheaply manufactured, and also to provide a structure which permits the manufacture 15 of a number of posts at one time, a plurality of mold units being provided, together with simple and efficient means for clamping the several units together. These objects are attained by a novel combination and arrangement of parts to be hereinafter described, reference being had to the accompanying drawings, in which—

Figure 1 is a plan view of the mold. Fig. 2 is a front elevation thereof showing 25 one of the end supporting members in section. Fig. 3 is a perspective view of a fragment of the mold. Fig. 4 is a cross section on the line 4—4 of Fig. 1. Fig. 5 is an elevation of a fragment of one end of the mold.

As shown in the drawings each mold unit 30 10 is a trough or U-shaped body of sheet metal, round or polygonal in cross-section, according to the desired shape of the post, and tapered toward one end. A number of 35 these units are mounted side by side in position for use and supported in such position by means to be presently described. The units are placed with the taper reversed alternately. The drawing shows four units, 40 but the number of units may be varied according to the number of posts to be made simultaneously.

The longitudinal rims of each unit 10 are beaded, one of the beads 11 being small and 45 having a wire reinforcement 12, and the other bead 13 being more open and larger so as to form a hook which catches over the bead 11 of the adjoining unit, and thus acts as a means of support.

The frame which holds or supports the 50 several mold units 10 herein described is constructed and arranged as follows: At the ends of the mold units are located wooden bars 15 having a rabbet 16 in the inner portion of their top edges. A rigid

sheet metal plate 17 is suitably secured to the inner face of each end bar 15 adjacent to the rabbet 16, the top edge of said plate rising to the level of the top of the end bar. The ends 18 of the wires 12 project from 60 the ends of the mold units and rest on the rabbeted portion of the end bars after passing through notches 19 in the top edge of the plates 17. Both ends of the mold units are supported in this manner by the end 65 bars 15. Against each end unit of the series of mold units is placed a longitudinal bar 20 which may be of channel steel or any other suitable material and extends throughout the entire length of the unit. These 70 bars engage the outer beads of the end units of the series, and they are held in recesses 21 in the beveled ends of the bars 15. The ends of the bars 20 are bent around against the outer face of the bars 15, and they are held 75 in place by pivoted latches 22, which latter, when swung to disengage the bars 20, permit removal of the latter. The bars 20 thus assist to support the end units of the series, and they also serve to prevent spreading of 80 the end bars 15 and hold the latter in place to support the mold units 10 therebetween.

An intermediate supporting member for the mold units 10 is also provided. This member is a transverse bar or casting 23 85 having top depressions 24 in which the mold units seat. At the outer ends of this transverse support 23 are top depressions 25 in which the bars 20 seat and are thus supported intermediate their ends. On one 90 side of each projecting end of the support 23 is pivoted, as indicated at 26, a latch bar 27 adapted to be placed across the adjacent bar 20 to assist the latches 22 in holding said bar against outward displacement. 95 The latch-bar is kept in holding position by a spring 28, coiled around the shank of the pivot bolt 26. This spring draws the pivot bolt tightly against the support 23, and the latter has a shoulder 29 against which the 100 lower end of the latch bar abuts. In this position, the latch bar cannot be swung to release the bar 20, its upper end engaging the latter. To release the latch bar it must be pressed outward against the spring until 105 it clears the shoulder 29, after which it can be swung away from the bar 20 as shown by dotted lines in Fig. 4. When the latch bars are to be placed in holding position, a slight pressure must be exerted on the mold 110

units so that they will give and allow the latch bars to spring and hold them tightly together.

It will be seen from the foregoing that the 5 mold units can be easily and quickly set up ready for use, and also knocked down, and the structure enables the posts to be rapidly and easily manufactured. The structure is also devoid of complicated parts liable to get 10 out of order, it is strong and durable, and it effectually serves the purpose for which it is designed. All the parts are interchangeable, and the mold units may be nested when not in use.

15 I claim:

1. In a post mold, a series of trough-shaped mold units placed side by side, end bars having a rabbeted top edge and a plate extending above the rabbet, said plate having a notched top edge, and the mold units having end projections passing through the notches of the plates and seating in the rabbets of the end bars, and means for holding the end bars against spreading.

2. In a post mold, a series of trough-shaped mold units placed side by side, end supports for said units, longitudinal bars fitting against the end units of the series and removably connected to the end supports, 20 and an intermediate support having seats

to receive the mold units, and end recesses in which the longitudinal bars removably seat.

3. In a post mold, a series of trough-shaped mold units placed side by side, end supports for said units, longitudinal bars fitting against the end units of the series and removably connected to the end supports, and an intermediate support having seats to receive the mold units, and latches 35 carried by the intermediate support and engageable with the longitudinal bars.

4. In a post mold, a series of trough-shaped mold units placed side by side, end supports for said units, longitudinal bars 40 fitting against the end units of the series and removably connected to the end supports, and an intermediate support having seats to receive the mold units, and end recesses in which the longitudinal bars removably 45 seat, and latches carried by the intermediate support and engageable with the longitudinal bars.

In testimony whereof I affix my signature in presence of two witnesses.

QUINCY G. SHELDON.
